PAIL OR SIMILAR ARTICLE

Roy G. Churan, Oak Lawn, Ill., assignor to Bennett Industries, Inc., Peotone, Ill., a corporation of Delaware

Continuation-in-part of design application Ser. No. 7,537, June 21, 1967. This application Feb. 28, 1968, Ser. No. 10,775

Term of patent 14 years

Int. Cl. D7—06
U.S. Cl. D49—29

FIGURE 1 is a front elevational view of a pail or similar article showing my new design, the rear being substantially the same in appearance;

This application is a continuation-in-part of applicant's co-pending design application entitled Open Head Container, Ser. No. D. 7,537, filed June 21, 1967.

I claim:

The ornamental design for a pail or similar article, substantially as shown and described.
